UNITED STATES PATENT OFFICE.

ERNEST EDWARD LEIGH, OF HALIFAX, CANADA, ASSIGNOR OF ONE-HALF
TO JOHN C. MAHON, OF SAME PLACE.

GAME.

SPECIFICATION forming part of Letters Patent No. 669,943, dated March 12, 1901.

Application filed February 15, 1900. Serial No. 5,346. (No model.)

To all whom it may concern:

Be it known that I, ERNEST EDWARD LEIGH, a citizen of the Dominion of Canada, and a resident of Halifax, in the county of Halifax 5 and Province of Nova Scotia, Canada, have invented certain new and useful Improvements in Games; and I do declare the following to be a full, clear, and exact description of the invention, such as will enable others 10 skilled in the art to which it appertains to make and use the same, reference being had to the accompanying drawings, and to letters of reference marked thereon, which form a part of this specification.

15 Figure 1 of the drawings is a plan view of the invention, partly broken away. Fig. 2 is a longitudinal section of the game apparatus. Fig. 3 is a cross-section of the game apparatus. Fig. 4 is a detail view of the carriage of one 20 of the movable figures.

This invention has relation to means of amusement; and it consists in the novel construction and combinations of parts constituting a game, the object of which is a competition trial of finger dexterity and endurance. 25

In this game the apparatus provided is a miniature race-course, with keys to be manipulated by the players to actuate the miniature horses, yachts, bicycles, or other figures 30 through suitable mechanism.

In the accompanying drawings the letter A designates the race-course or board, which in the construction illustrated has separate oblong horizontal tracks B B, of endless character, arranged side by side, said tracks being 35 slots through a top board or plate C, which is supported by posts D, extending up from the base E.

F represents the casing.

40 G G designate two sets of keys g, which are formed somewhat after the style of piano-keys and project laterally below the top board of the race-course, being pivoted to bearings intermediately, as indicated at H. The keys 45 g are provided with springs k, which are arranged to return the keys to their normal position after they have been pressed down by the fingers. When the keys are operated by the fingers, they actuate mechanism which

is designed to move the miniature horses or 50 other figures L L around the race-tracks with varying speed in accordance with the rapidity with which the keys are vibrated. For this purpose I employ the vibratory boards or figure-carriers V V, which extend lengthwise below the race-slots and are connected to the end posts D by means of apertures m m, which loosely fit said posts in such a manner that the boards V V can easily move up and down. In order to prevent these boards 55 from moving upward too much, the check-pins or stops p p are provided in the posts. Each board V is supported at its ends on the outer ends of tipping levers S S, which are pivoted near their adjacent ends on a pin t. The 60 short arms s s of these levers are engaged by the bottoms of the keys, and when either key is depressed it actuates a lever S, which in turn throws, by means of its long arm, one end of the vibratory board upward. Alternately the pressure on the other key of the set 65 throws up the other end of said board, while the rising of the first key allows the end of the board first raised to suddenly drop. This intermittent vibratory action of these boards 70 is designed to cause the small figures thereon to progress around the track with such speed as the rapidity of manipulation of the keys 75 shall impart.

Instead of using the vibratory boards and 80 figures moving thereon the figures may be attached to ratchet-chains engaging end pulleys and operated by spring-pawls connected to the keys.

In playing this game each competitor works 85 one set of keys by such rapid vibratory action of his fingers as he is able to accomplish and in this manner causes the movement of his racing-figure. Persons who are accustomed to playing upon a piano will usually have 90 some advantage in the game, but not always.

The apparatus is not only designed as a means of amusement, but also as a means of exercise for the fingers, which is not without benefit.

Upon operation of the vibratory keys the levers S S are raised at one end, the operation of a key at one side of the board raising or 95

tipping the lever at the opposite side of the board, and vice versa. In this way the vibratory boards V are raised at one end or the other, which causes the figures L to slide 5 down upon said boards in the slots or tracks.

Having described this invention, what I claim, and desire to secure by Letters Patent, is—

1. In a race-game apparatus, the combination with the two sets of vibratory keys, the movable figures, and the race-course board, of independent sets of intermittently-acting figure-moving mechanism engaged by said keys, substantially as specified.
- 15 2. In a race-game apparatus, the combination with a set of vibratory keys and the slotted race-course board, of the movable figures, and intermittently-acting figure-moving mechanism, operative through alternate engagement of the keys of the set, substantially as specified.
- 20 3. In a race-game apparatus, sets of alternately-acting vibratory keys, movable figures, and independent sets of intermittently-acting

figure-moving mechanism, substantially as 25 specified.

4. In race-game apparatus, the combination with movable figures and sets of alternately-acting vibratory keys, of the slotted race-course board, the figure-carriers arranged to be tipped from opposite ends, and devices actuated by said keys and engaging said figure-carriers to tip the same, substantially as specified.

5. In race-game apparatus, the combination with a board, having endless tracks of equal length, of figures adapted to move around said tracks, and means for effecting movement of a figure of each track independently consisting of tilttable figure-carriers, 35 and vibratory keys arranged to tilt said carriers, substantially as specified.

In testimony whereof I affix my signature in presence of two witnesses.

ERNEST EDWARD LEIGH.
